BROOKLYN, NEW YORK.

TOP.

1,210,098.

Specification of Letters Patent. Patented Dec. 26, 1916.

Application filed July 17, 1915. Serial No. 40,452.

To all whom it may concern:

Be it known that I, FREDERICK A. PICKETT, a citizen of the United States, residing at Baltimore, in the State of Maryland, have 5 invented certain new and useful Improvements in Tops; and I do hereby declare the following to be a full, clear, and exact description of the invention, such as will enable others skilled in the art to which it 10 appertains to make and use the same.

This invention relates to tops and top spinning devices, and the primary object of the invention is to construct a top having a novel form of plate which is attached to the 15 butt of a top for detachable connection with a spinning structure, which includes a spiral shaft or rod composed of a pair of twisted wires, a nut member for slidable rotary movement over said spiral shaft or rod for 20 imparting rotation thereto, and a swivelly connected handle, which is attached to the upper end of said spiral shaft or rod, for holding the same during its spinning rotation and further to construct the plate which 25 is attached to the butt of a top, so that when a spinning rotation is imparted to the spiral shaft or rod, in one direction, the top will be disconnected from the rod and will spin on the floor, or any suitable structure, thereby 30 providing means for easily spinning a top and eliminating the use of the usual type of top string or cord which must be tediously wound about the outer surface of the top.

With the foregoing and other objects in view, this invention consists in such novel features of construction, combination and arrangement of parts as will be hereinafter more fully described illustrated in the accompanying drawings and claimed.

In describing the invention in detail, reference will be had to the accompanying drawings wherein like characters designate like and corresponding parts throughout the 45 several views, and in which:

Figure 1 is a side elevation of the improved top and spinning means showing parts thereof in section. Fig. 2 is a perspective view of the nut used for spinning or rotating the spiral rod. Fig. 3 is a bottom plan view of the nut. Fig. 4 is a sectional view on the line 4—4 of Fig. 1. Fig. 5 is a vertical section through the upper butt end of the top and the lower end of the 50 spiral spinning rod. Fig. 6 is a top plan

view of the top, and Fig. 7 is a cross sectional view on the line 7—7 of Fig. 1.

Referring more particularly to the drawings, 1 designates a top of ordinary construction, having a spinning point 2 and 60 a butt 3. The top of the butt 3 of the spinning top 1 has a metallic plate 4 secured thereto, which plate is provided with a central opening 5. The opening 5 communicates with an opening 6, which is centrally 65 disposed and extends downwardly into the butt 3 of the top 1 and which has a sleeve 7 positioned in and forming a lining for the same. The plate 4 has two sections 8 and 9 cut free from the same and rolled upwardly 70 from the plate and the top of the butt 3. The sections 8 and 9, are formed by cutting two arcuate slits indicated at 10, extending a portion of the circumference of a circle 75 scribed from the central axis of the top, and by the cutting of slits 11 which extend substantially transversely to the arcuate slits 10. The bulged portions of the members 8 and 9 gradually taper inwardly toward the butt of the top as they extend away from the slits 11, so as to provide a friction lock 80 for engagement with a cross pin 12. The pin 12 is carried by and extends diametrically through the lower end of the section 13 of the spiral rod or shaft 14. A sleeve or 85 collar 15 is mounted about the lower end of the rod or section 13, and the pin 12 extends through the sleeve and the lower end of the rod or section 13, a short distance above the lower ends of the same.

The spiral rod or shaft 14 is formed of 90 two sections 13 and 16, which are twisted for forming the spiral rod. The upper end of the rod 13 terminates below the upper end of the section or rod 16. The section or rod 95 16 has a head 17 formed upon its upper terminal which head is positioned intermediate the bright portion 18 of the U-shaped shaft 19 and the under surface of a handle 20 to which the legs of the U-shaped shaft are 100 attached. The bright portion 18, through which the upper end of the section 16 extends is provided with an opening 21, which is greater in diameter than the diameter of the section 16 so as to permit of a swiveled 105 connection between the spiral shaft or rod 14 and the handle 20. A wear plate 22 is positioned in the lower end of the handle 20 and for engagement with the head 17 for preventing of the wearing of the handle by 110 113

the rotary or swiveled action of the spiral rod 14.

The lower end of the section 16 of the rod or shaft 14 is bent outwardly, as is shown at 24, transversely to the body of the rod 14 and forms a stop for limiting the downward slidable movement of a nut 25, which is mounted upon the spiral rod 14. The nut 25 is provided with a central opening or bore 26, within which is coiled a length of wire 27. The lower end of the nut 25 is provided with an opening 28 formed therein which extends inwardly toward the bore 26 of the nut and provides a recess for receiving the lower end 30 of the twisted length of wire 27. A staple 31 may be applied for securingly holding the end 30 within the recess 28. An annular flange 32 is formed upon the lower end of the nut 25 the upper edge of which forms an abutment against which the end of an operator's thumb and a portion of the index finger rest when sliding the nut 25 longitudinally upon the spiral rod 14.

25 When it is desired to spin the top 1, the pin 12 is placed beneath the outstruck bulged portions 8 and 9, as shown in Figs. 1 and 5 of the drawings. The friction between the end of the pin 12 and the inner surfaces of the bulged out portions 8 and 9 will hold the top and rod 14 as under ordinary conditions. The nut 25 is preferably moved to the upper end of the spiral rod or shaft 14 prior to the connection between the lower end of the shaft or rod and the top 1. The nut 25 is then moved downwardly over the spiral rod 14 toward the top 1, which rotates the rod and consequently the top 1, which is connected to its lower edge. The wire 27 which is twisted within the bore 26 of the nut 25, meshes with the depression formed in the spiral rod 14, and causes the latter to rotate when the nut 25 is moved longitudinally along the rod.

40 45 The rotation of the spiral rod 14 occasioned by the downward movement of the nut 25 toward the top 1, will impart rotary motion to the top, and when the centrifugal force of the rotation of the top becomes great enough to overcome the frictional contact between the rod or pin 12 and the sections 8 and 9, the top will be disconnected from the rod and fall spinning upon the floor, ground or any other suitable surface. 50 55 The reverse rotation of the rod 14, occasioned by the upward movement of the nut 25 upon the spiral rod 14 will not disconnect the top 1 from the rod, owing to the fact that this rotation of the top tends to move the pin 12 inwardly within the por-

tions 8 and 9 and increase the strength of the connection between the rod 12 and the members 8 and 9, while the downward movement of the nut rotates the rod 14 in the direction, so that the force of the rotation of the top will cause the same to move, in the direction necessary to permit the ends of the rod 12 to pass out of the portions 8 and 9 through the substantially transversely extending slit 11.

70 From the foregoing description taken in connection with the accompanying drawings the advantages of construction and of the method of operation of the improved top will be readily apparent to those skilled in the art to which the invention appertains and, while in the foregoing description the principle of the operation of this invention has been described together with various features of construction, it is to be understood that certain minor features of construction, combination and arrangement of parts may be altered to suit practical conditions provided such alterations are comprehended within the scope of what is claimed.

80 85 What is claimed is:—

1. A device of the character set forth comprising a handle, a spirally formed rod swiveled to said handle, a second spirally formed rod interlaced with the first mentioned rod and having its lower end bent at right angles to form a stop, a nut mounted on said rods for rotating the rods upon sliding of the nut, and means for detachably securing the first mentioned rod with a top.

90 95 2. A device of the character set forth comprising a handle, a spiral rod swiveled to said handle, a nut mounted on said rod, a coil wire within said nut for an engagement with the spiral rod to rotate said rod upon sliding the nut, and means for detachably securing the rod to a top.

100 105 3. A device of the character set forth comprising a handle, a spiral rod swiveled to said handle, means for detachably securing a top to the rod, a substantially cylindrical nut mounted on said rod and provided with a groove, a coiled wire within said nut for an engagement with the spiral rod and having its lower end bent to extend into the groove, and a staple for securing the end of the coiled wire in the groove.

110 In testimony whereof I affix my signature in presence of two witnesses.
